Fig. 3 128

A technical diagram of an organ stop board. It features a grid of 15 vertical tubes arranged in three rows of five. Above the board, various stop labels are positioned: '19' and '10' on the left, '130' in the center, '11' and '(34)' to the right of the center, '55' further right, '129' at the far right, '128' at the top right, '131' on the far left, '18' and '35' at the bottom left, '131' at the bottom center, '12' at the bottom right, and '54' at the bottom right. The labels are connected to specific tubes by lines.

poration of Delaware

Application February 5, 1936, Serial No. 62,459

12 Claims. (Cl. 177—346)

This invention relates to electric illumination intensity control systems and more particularly to systems and apparatus for controlling the degree of energization in lighting circuits employed for outdoor and indoor ornamental and display lighting.

An object of the invention is to provide a novel illumination intensity control system wherein a multiplicity of intensities of illumination for a group of lamps may be preselected and wherein means are provided for effecting gradual transition from one preselected intensity of illumination to another in uniform increments and decrements substantially proportional to the difference in said preselected intensities.

Another object is to provide a system of the aforementioned character wherein novel means are provided for effecting a continuous cycle of variations in the intensities of illumination of the group of lamps in accordance with the values of intensity preselected therefor.

Another object is to provide a system of the aforementioned character wherein means are provided for simultaneously effecting the changes in illumination intensities of a plurality of groups of lamps in accordance with the values of intensity preselected for the respective groups.

Another object is to provide a novel arrangement of the control parts of the system whereby the degrees and rates of change of the illumination intensities of the respective groups of lamps may be visually indicated in advance.

Various other objects and advantages of the invention will hereinafter appear.

The accompanying drawings illustrate certain embodiments of the invention which will now be described, it being understood that the invention is susceptible of embodiment in other forms without departing from the scope of the appended claims.

In the drawings,

Figure 1 illustrates schematically and diagrammatically an illumination intensity control system embodying my invention.

Fig. 2 is a similar view of a modified form of illumination intensity control system.

Fig. 3 is a plan view of a control panel which may be embodied in each of the systems illustrated in the drawings,—one form of gag plate which may be employed in conjunction with the control elements of the device being shown in position on the control panel.

Fig. 4 is a diagram which shows by means of curves the characteristics of illumination in-

tensity control which are obtained with the systems illustrated in Figs. 1 and 2.

Referring first to Fig. 1 of the drawings,—I have illustrated, by way of example, three groups of electric lamps, continuity of circuit and intensity of illumination of the lamps in the respective groups being subject to control by a system constructed in accordance with my invention; it being understood that in practice a larger number of lamp groups will ordinarily be employed,—the control elements being merely duplicated for each additional group of lamps. The three groups of lamps are designated in general by the reference characters 1, 2 and 3. It is to be understood, of course, that any desired number of lamps may be embodied in each group.

The groups of lamps 1, 2, 3 are adapted to be connected across and supplied with current from the direct current supply lines designated as L¹, L². The supply of current to the lamps is controlled by suitable controlling devices, such as the dimmer rheostats designated respectively by the numerals 4, 5 and 6.

Assuming energization of the groups of lamps, the intensity of illumination of the lamps in each group is dependent upon the respective positions of the adjustable contact arms 7, 8 and 9 of the dimmer rheostats, said contact arms to be hereinafter referred to as dimmer arms. Each of said dimmer arms 7, 8 and 9 is shown in a position corresponding to the respective positions of the manually adjustable contact arms 10, 11 and 12, which are associated respectively with the sending rheostats 13, 14 and 15, said last mentioned contact arms to be hereinafter referred to as sender arms. Thus dimmer arm 7 is shown in mid-position to provide, say, half-bright illumination intensity of the lamps of group 1, dimmer arm 8 is shown in its upper extreme position to provide full-bright illumination intensity of the lamps of group 2, and dimmer arm 9 is shown in its lower extreme position to provide for substantially black-out condition of the lamps in group 3.

Means are associated with each group of lamps to provide for movement or adjustment of the dimmer arms 7, 8 and 9 automatically from any given position or positions thereof to any other position or positions,—the position or positions to be assumed by each of said dimmer arms being initially preselected individually, as by the aforementioned sender arms 10, 11 and 12. These positions may be preselected during rehearsal to provide the desired illumination effect of certain or all of the groups of lamps.

jointly,—whereupon the adjustments so effected may be definitely registered upon a suitable gag plate or the like to provide for subsequent enactment of the exact illumination effect so pre-selected.

- 5 As shown in connection with the lamp group 1 the means for preselecting the positions and for controlling movement of dimmer arm 7 comprises essentially the aforementioned sending 10 rheostat 13 with its associated sender arm 10, and in addition, the sending rheostats 16, 17, sender arms 18, 19 associated with said rheostats respectively, a receiving rheostat 20, an adjustable contact arm 21 to cooperate therewith,— 15 said arm to be hereinafter referred to as receiver arm,—and the coil 22 of a polarized relay of known form,—said receiving rheostat 20 and polarized relay coil 22 being connected with respect to each other and with respect to lines L¹, 20 L² and selectively connectable with respect to sending rheostats 13, 16 and 17 in the form of a Wheatstone bridge. It is understood that a considerably larger number of sending rheostats may be employed in practice.
- 25 A resistance, connected in an electrically closed loop, is divided into three sections 23, 24, 25, said sections corresponding in number to the number of sending rheostats. Said fader resistance sections 23, 24, 25 are adapted to be introduced into said Wheatstone bridge circuit by an adjustable contact arm 26, said arm to be hereinafter referred to as fader arm,—to modify the controlling effect of said sending rheostats in a manner which will hereinafter be more fully described. It will be understood that the number 30 of fader resistance sections required corresponds in all cases to the number of sending rheostats employed.

The contactor 27 of the polarized relay is normally biased to an intermediate or neutral position, as illustrated, when the bridge circuit is in balanced condition, and the same is moved automatically into engagement with the stationary contacts 28, 29 selectively, depending upon the 40 sense in which the bridge circuit is unbalanced. Engagement of stationary contact 28 by contactor 27 effects energization of a switch 30, response of which connects field winding F of a split-field reversible motor M across lines L¹, L² 45 to effect operation of said motor in one direction, whereas engagement of stationary contact 29 by said contactor effects response of a switch 31 to energize said motor through its other field winding F' to effect operation of said motor in 50 the opposite direction.

The means for preselecting the positions and for controlling the movement of dimmer arm 8 comprises a Wheatstone bridge circuit including sending rheostats 14, 32, 33 and their associated 60 sender arms 11, 34, 35, respectively, receiving rheostat 36 and its associated receiver arm 37, a polarized relay having a coil 38, contactor 39, and stationary contacts 40, 41, and fader resistors 42, 43, 44 and other associated fader arm 65. Similarly, the Wheatstone bridge control 70 means for dimmer arm 9 includes sending rheostats 15, 52, 53 and sender arms 12, 54, 55, receiving rheostat 56 and receiver arm 57, polarized relay coil 58, contactor 59 and stationary contacts 60, 61 and fading resistors 62, 63, 64 and fader arm 65. As will be noted the aforementioned control means for the groups of lamps 2 and 3 include switches corresponding to the 75 switches 30 and 31 embodied in the control means for the lamp group 1. The driving means for the

receiver arms 37, 57 comprises the motors M¹, M², respectively, which may be identical with the motor M aforescribed.

If desired, switches 70, 71, 72 may be provided, the same being adapted to control continuity of 5 circuit of the respective lamp groups and to render ineffective their associated control apparatus.

The sender arms associated with the respective groups of sending rheostats are connected between the fader resistance sections comprising 10 the aforementioned closed loops,—sender arm 10 being connected between fader resistors 23, 25, arm 18 being connected between resistors 23, 24, and arm 19 being connected between resistors 24, 25. Sender arms 11, 34, 35 and 12, 54, 55 are 15 similarly connected with respect to fader resistors 42, 43, 44 and 62, 63, 64 respectively.

The fader arms 26, 45, 65 associated respectively with each of the sets of fader resistors, are adapted to be moved simultaneously and in 20 like directions over said resistors by a pilot motor 74 through the medium of suitable reduction gearing, designated by the reference numeral 75, and a drive shaft 76. Said shaft 76 carries the gear wheels 77, 78, 79, which are in driving engagement with the gear wheels 80, 81, 82, respectively, said last mentioned gear wheels carrying the respective fader arms 26, 45, 65. Movement of said fader arms effects variation of the intensity of illumination of the groups of lamps in 30 a smooth, gradual manner from one preselected value to the next, said values being in accordance with the setting of the sender arms. The resistance of the fader resistors, the resistance of the sending rheostats and the receiving rheostat and the resistance of the polarized relay coil in each control circuit are so proportioned with respect to each other as to afford a substantially straight line transition from one preselected intensity of illumination to the next.

For example, assuming the potential across lines L¹ and L² to be 120 volts, and the resistance values of the sending and receiving rheostats and the polarized relay coil each to be 1200 ohms, it has been found that the aforescribed results 40 are obtained by using a fader resistor whose respective sections have resistance values of 3000 ohms. Depending upon the degree of sensitivity of the polarized relay, the relatively higher ohmic value of the individual fader resistor sections obviously may be greater or less than the value 45 aforementioned as compared with the values of the sending and receiving rheostats.

Further details of construction of my illumination control system and one method of operating 55 the same will now be described, chiefly in connection with lamp group 1. Closure of switch 70 energizes lamp group 1 and its associated control circuit. Assuming the various control elements to be in the positions illustrated, the intensity of illumination of lamp group 1 will be 60 at half-bright. Closure of the pushbutton switch 83 effects operation of the pilot motor 74 to effect simultaneous movement of the fader arms 26, 45, 65 in a clockwise direction, for instance. 65 Immediately upon inclusion of a portion of fader resistor 23 the Wheatstone bridge circuit becomes unbalanced in a direction to effect engagement by the polarized relay contactor 27 of the stationary contact 28, for instance, to energize the winding of switch 30. Switch 30 responds to energize motor M through its field winding F for operation in a direction to effect downward movement of receiver arm 21 and dimmer arm 7 through the 70 medium of suitable gearing indicated at 84. Said 75

receiver arm and said dimmer arm are shown as being mechanically connected with but electrically insulated from each other.

As the fader arm 26 continues its movement over the fader resistor 23 the Wheatstone bridge circuit continues to remain unbalanced, the polarized relay effecting control of motor M for effecting gradual downward movement of dimmer arm 7 and receiver arm 21, movement of the latter tending to restore the bridge circuit to balanced condition.

The motors M, M¹, M² and the pilot motor 74 should preferably be so arranged that the rate of movement of the dimmer arms is somewhat greater than that of the fader arms, so that there is virtually no lag in the movement of the dimmer arm with respect to the movement of the fader arm. I prefer to include an adjustable resistance 85 in circuit with the pilot motor 74 to provide for insuring the desired speed relation between the fader arms and the dimmer arms. Obviously speed control for the motors M, M¹, M² may be provided, but this has been omitted from the disclosure to simplify the same.

When the fader arm 26 reaches the point between fader resistors 23 and 24 the sender arm 18 becomes wholly effective and the dimmer arm 7 substantially simultaneously reaches its lower extreme position, corresponding to the position of said sender arm 18. The lamps of group 1 will then be in substantially black out condition.

As the fader arm 26 continues to move it traverses the fader resistor 24 which is connected between the sender arms 18 and 19. Upon inclusion of a portion of said fader resistor 24 the Wheatstone bridge circuit becomes unbalanced in a direction to effect engagement by the polarized relay contactor 27 of the stationary contact 28; whereupon switch 31 responds to energize the motor M through its field winding F¹ for operation in a direction to effect upward movement of receiver arm 21 and dimmer arm 7.

When the fader arm 26 reaches the point between fader resistors 24 and 25 the sender arm 19 becomes wholly effective, and substantially simultaneously the dimmer arm 7 reaches its upper extreme position. The lamps of group 1 will then be at full-bright illumination intensity, the circuit thereof being obvious.

Continued movement of the fader arm 26 will effect unbalancing of the Wheatstone bridge circuit to effect downward movement of the dimmer arm 7 to a position corresponding to the position of the sender arm 10 to again provide half-bright illumination intensity of the lamps of group 1.

It will be apparent that the aforescribed cycle of operation will be repeated continuously as long as the pilot motor 74 is in operation.

Assuming closure of switches 71, 72, illumination intensity variations will take place in the lamps of groups 2, 3 simultaneously with the illumination intensity variations being effected in the lamps of group 1. Thus, as aforescribed, the illustrated position of dimmer arm 8 provides for full-bright illumination intensity of the lamps in group 2, said dimmer arm being adapted to be moved from said position in the manner described in connection with dimmer arm 7 to positions which provide for variation of the illumination intensity from full-bright to half-bright, from half-bright to black-out and then back to full-bright, in accordance with the preselected positions of sender arms 11, 34, 35, respectively.

The illustrated position of dimmer arm 9, as aforescribed, provides for substantially black-

out condition of the lamps of group 3, and said dimmer arm is adapted to be moved from said position to positions which provide for variation of the illumination intensity of said lamps from black-out to one-quarter bright, from one-quarter bright to three-quarters bright and then back to black-out, in accordance with the preselected positions of sender arms 12, 54, 55, respectively.

The aforescribed cycles of variation in the intensity of illumination of the groups of lamps 1, 2, 3 are represented by the curves shown in the diagram, Fig. 4. The solid line represents the illumination intensity characteristic of the lamps of group 1; the dotted line and the dot and dash line represent the illumination intensity characteristics of the lamps of groups 2 and 3, respectively. The small circles in the respective curves represent the preselected intensities of illumination as determined by the positions of the sender arms. Thus circles A represent the intensities preselected respectively, by sender arms 19, 10, 18; circles B represent the respective intensities preselected by sender arms 35, 11, 34; and circles C represent the respective intensities preselected by sender arms 55, 12, 54.

It will be obvious to those skilled in the art that a system of the character aforescribed affords extreme flexibility in the character of illumination intensity control of the various lamp groups, it being obvious that all or any portion of the complete range of adjustment of the illumination intensity of each group of lamps may be utilized by the individual sender arms associated therewith, and that regardless of the portion of the complete range of adjustment of the illumination intensity utilized for any other group or groups of lamps. Also it will be apparent that the system provides for decreasing or increasing the intensity of illumination of one or more of the groups of lamps during the increasing or decreasing of the intensity of illumination of other of said groups of lamps.

Fig. 2 illustrates an embodiment of the invention wherein the illumination intensity of the lamps in each of the groups 1, 2 and 3 is regulated through the medium of a variable inductance device. The variable inductance device is provided with an exciting winding, and as is well known, variations of the current in such winding produce variations in the voltage drop in the inductance device and thus variations of the lamp voltage. The current in the exciting winding is controlled by means of an electron tube whose impedance may be varied by impressing upon a control grid of such tube a voltage which is the resultant of a variable control voltage and a voltage which depends upon and varies in accordance with the lamp voltage. Thus, regardless of the value of the lamp load, the voltage across the lamps and hence the illumination intensity of the lamps will be substantially the same for a given control voltage.

Referring to Fig. 2, L¹¹ and L¹² are the terminals of an alternating current constant potential source of supply. The elements in this embodiment of the invention which correspond to the elements in the embodiment of Fig. 1 are designated by corresponding reference numerals. Thus 1, 2 and 3 indicate the groups of lamps, the voltage of which is to be regulated. The lamps of group 1 are connected in series with the coils 101 of a variable reactor 104 and across the lines L¹¹ and L¹². Said reactor 104 has an exciting winding 107 which is connected in series with the electron tube 110 across the lines L¹¹ and L¹².

Electron tube 110 has a cathode 111 which may be heated in any well known manner, an anode 112 and a control electrode or grid 113. Connected in parallel with the winding 107 is a half wave rectifier 114, the purpose of which is to smooth out in a well known manner the ripples of the current in the winding 107 as supplied through the electron tube 110.

A transformer 115 has a primary winding 116 connected in parallel with the lamps 1, while one terminal of its secondary winding 117 is connected to the control grid 113 and the other terminal is connected to a half wave rectifier 118. An energy storage discharge circuit, consisting of 15 a condenser 119 and a resistor 120 connected in parallel with said condenser, is connected at one end between the transformer secondary winding 117 and the control grid 113, and at the other end to the rectifier 118. A second transformer 121 20 has its primary winding 122 connected between fader arm 26 and line L¹², while one terminal of its secondary winding 123 is connected to a half wave rectifier 124 and the other terminal is connected to cathode 111 and to one end of a second 25 energy storage discharge circuit consisting of a condenser 125 and a resistor 126 connected in parallel therewith, the other end of said last mentioned energy storage discharge circuit being connected between the rectifier 124 and said first 30 mentioned energy storage discharge circuit.

The sending rheostats 13, 16, 17 are connected in parallel across the lines L¹¹ and L¹² and the fader resistors 23, 24, 25 are connected with respect to said rheostats as described in connection 35 with Fig. 1. The sender and fader arms in Fig. 2 are shown in positions corresponding to those shown in Fig. 1 and may be assumed to provide for similar results in the control of the illumination intensity of the lamps in the respective 40 groups.

The system operates in the following manner:—Current flows between the lines L¹¹ and L¹² through the coils 101 of the reactor 104 and the lamps 1. The voltage drop through the coils 101 45 varies in accordance with the energization of the coil 107 in a well known manner. The current in the coil 107 is controlled by controlling the instantaneous voltage of the grid 113 during the positive half cycle, during which the tube 110 permits current flow therethrough, provided that the voltage of the grid 113 is more positive than the critical voltage thereof. It will be noted that the voltage of the grid 113 with respect to the cathode 111 at any moment is the resultant of 50 the instantaneous voltage of the condenser 119 and the condenser 125,—the two being connected in series. The condenser 119 is charged by a voltage impressed upon it by the secondary winding 117 of the transformer 115 through the rectifier 118, said voltage being proportional to the lamp voltage. The rate of discharge of the condenser 119 is determined by the value of the resistance 120.

A voltage is impressed upon the condenser 125 65 through the secondary winding 123 of the transformer 121, this voltage being a function of the adjustment of the sending rheostats 13, 16, 17 and of the fader resistors 23, 24, 25, depending upon which of the rheostats and resistors is rendered effective by the fader arm 26.

In normal operation the fader arm 26 is moved gradually over the fader resistors 23, 24, 25, and as it moves from its illustrated position it causes a difference between the voltage of the condenser 75 119 and the voltage of the condenser 125, the

voltage of the latter corresponding at the first moment of change to the initial voltage of the lamps. Thus the resultant voltage from the two discharge circuits which is impressed upon the grid 113 is varied, causing a change in the current impressed upon the coil 107 and thus a change in the voltage supplied to the lamps. As the lamp voltage approaches the new value the voltage impressed on the condenser 119 varies due to the influence of the transformer 115 until 10 when the new lamp voltage is attained the voltage of the two discharge circuits balance to a value at which no further change takes place in the current flowing through the tube 110 and the winding 107. Obviously, as long as the fader arm 15 26 continues to move, the two discharge circuits tend to become balanced but remain slightly out of balance, so that there is a gradual follow-up by the lamp voltage of the voltage controlled by the fader arm 26 and the sender arms 10, 18, 19. 20

As previously stated herein, and as will be apparent, the control system of Fig. 2, aforescribed, affords a character of illumination intensity control similar to that afforded by the control system of Fig. 1.

It will be obvious to those skilled in the art that the sender arm taps which are shown as being connected between the fader resistor sections may be rendered adjustable to vary the characteristics and rates of illumination intensity 30 changes between the values preselected by the respective sender arms.

A convenient arrangement of the sender arms upon a control panel 127 is illustrated in Fig. 3. It should be noted that the sender arms are arranged in a manner whereby the sets of arms associated with the respective lamp groups serve to visually indicate by their relative positions the degree and character of changes of illumination 35 intensity to be effected sequentially in respect of 40 the several groups of lamps, and the relative rates at which such changes are to be effected, as shown in Fig. 3 by the dotted lines projected between the several sender arm handles.

A removable gag plate 128 is shown mounted 45 on the control panel 127, said gag plate being provided with slots 129, which accommodate the projecting handles of the sender arms 10, 18, 19, 11, 34, 35, 12, 54, 55. Slots 129 are arranged alternately with respect to the slots 130, within 50 which the adjustable latch members 131 are adapted to slide.

After a desired illumination effect is obtained by movement of the respective sender arms to various trial positions, the gag plate 128 is set in 55 place on the panel and the latch members 131 are moved into and clamped in positions corresponding to the instant positions of the sender arms. Latch members 131 may serve merely as markers, or may be provided with means engageable with 60 the sender arms to definitely position the same. Thus by means of a multiplicity of gag plates any number of illumination effects may be registered and subsequently repeated without the necessity of again having to obtain the desired effects by 65 trial manipulation of the sender arms.

The gag plate 128 and the latch members 131 may be and preferably are similar to the gag plate and latch members shown and described in my patent, No. 1,932,040, dated October 24, 70 1933.

While the system shown in Fig. 2 will operate satisfactorily with the sending rheostats and the fader resistor sections being of such ohmic values relative to each other as are suitable to effect 75

- operation of the polarized relay of Fig. 1, it is to be understood that in practice fader resistor sections of relatively greater ohmic value are employed, since the grid control instrumentalities, consisting of the energy storage discharge network, are very much more sensitive than the polarized relay and therefore require a relatively smaller current to operate, as is well known. Moreover, it will be apparent to those skilled in the art that the actual voltage curve obtained with the system of Fig. 1 will depart slightly from an exact linear curve, but that the system of Fig. 2 will provide a voltage curve which follows very closely the curve of illumination intensity which is shown in Fig. 4. Thus, if an extremely exact curve of illumination intensity is required, the system shown in Fig. 2 would be preferable. However, since the important consideration is the visual effect or effect upon the eye of an observer, slight departures of the voltage in the lamp circuit from an exact linear curve are of practically no consequence, since there is little or no observable effect of variation of illumination intensity of the lamps due to such departures in voltage.
- What I claim as new and desire to secure by Letters Patent is:
1. In a control system, in combination, a load circuit having a connection with a source of constant potential, regulating means for said load circuit, means for operating said regulating means to vary the degree of energization of said load circuit, said operating means comprising sending means and receiving means connected with the latter in the form of a balancing control circuit, said sending means comprising a plurality of variable potentiometer resistors connected in parallel for preselecting a plurality of values of potential to be derived from said source, each of said values determining a point of balance of said control circuit, whereby given degrees of energization of said load circuit are selected, a fader resistor comprising a plurality of resistor sections connected in an electrically closed loop, the extremities of each of said resistor sections being subjected respectively to certain of said selected potential values, a fader contact arm cooperating with said fader resistor and movable with respect thereto to gradually vary the potential between the preselected values for each fader resistor section in increments or decrements substantially proportional to the difference in said values, whereby the point of balance of said control circuit is gradually changed with respect to said determined points, and associated means operable by unbalance of said circuit automatically to restore balance of said control circuit at the point determined by the position of said fader contact arm, and simultaneously to operate said regulating means to subject said load circuit to a varying degree of energization having a direct relationship to said control potential.
  2. In a control system, in combination, a load circuit having a connection with a source of constant potential, regulating means for said load circuit, means for operating said regulating means comprising a plurality of resistors connected in parallel across a suitable source, each of said resistors having a cooperating contact arm presetable to select a control potential, a fader resistor connected in an electrically closed loop to which said contact arms are connected at spaced points, a cooperating fader arm movable with respect to said fader resistor to gradually vary the potential between the selected potentials in increments or decrements substantially proportional to the difference in the values of the selected potentials, means connected with the aforesaid resistors in the form of a balancing control circuit, the point of balance of said control circuit being gradually changed by variation of said control potential, and associated means responsive automatically to unbalance of said control circuit to restore balance thereof, said last mentioned means being operable simultaneously to operate said regulating means to subject said load circuit to a varying degree of energization having a direct relationship to said varying control potential.
  3. The combination with an illumination circuit to be supplied from a suitable source, of regulating means for varying the degree of energization of said illumination circuit, operating means for said regulating means, said operating means including sending means and receiving means connected with the latter in the form of a balancing control circuit, said sending means comprising a plurality of sending resistors the terminals of which are subjected to like degrees of potential, each of said resistors having a sender arm associated therewith and movable with respect thereto for preselecting values of control potential, whereby given points of balance of said control circuit are determined, means for gradually changing the point of balance of said control circuit with respect to said predetermined points, said last mentioned means comprising a fader resistor connected in an electrically closed loop to which said sender arms are connected at spaced points, a fader arm associated with said fader resistor and movable with respect thereto, whereby said control potential is adapted to be varied substantially rectilinearly between said preselected values, and associated means operable by unbalance of said control circuit automatically to restore balance thereof, and simultaneously to operate said regulating means to subject said illumination circuit to a varying degree of energization in accordance with variation of said control potential.
  4. The combination with an illumination circuit to be supplied from a suitable source, of a fader resistor connected in an electrically closed loop, means comprising a plurality of sending rheostats connected in parallel across said source and each having an adjustable sender arm associated therewith, said sender arms being electrically connected with said fader resistor at spaced points on the latter whereby said fader resistor is connected with said source, said means being adapted to subject the fader resistor at said points of connection to selected values of potential, an adjustable contact arm associated with said fader resistor, and means associated with said contact arm for subjecting said illumination circuit to potential conditions which are the effect of the differential value of a plurality of said selected potential values as modified by a selected value of the resistance of one of said fader resistor sections.
  5. The combination with an illumination circuit to be supplied from a source of constant potential, of regulating means for said circuit, operating means for said regulating means including sending means and receiving means connected with the latter in the form of a balancing control circuit and associated means operable by unbalance of said control circuit automatically to restore balance thereof, and simultaneously to operate said regulating means to

- subject said illumination circuit to a degree of energization determined by the point of balance of said control circuit, said sending means comprising a plurality of sending rheostats connected in parallel across said source and each having an adjustable sender arm associated therewith for determining a point of balance of said control circuit, a fader resistor having a plurality of resistor sections connected in the 10 form of an electrically closed loop, said sender arms being connected to the extremities of said fader resistor sections, respectively, and a fader arm associated with said fader resistor and adapted to traverse said fader resistor sections 15 in sequence to gradually change the point of balance of said control circuit with respect to said predetermined points of balance, whereby the degree of energization of said illumination circuit is varied substantially rectilinearly between values corresponding to said predetermined 20 points of balance.
6. The combination with an illumination control circuit to be supplied from a source of constant potential, of means for regulating the degree of energization of said illumination circuit, means for operating said regulating means, said operating means comprising sending means and receiving means connected with the latter in the form of a balancing control circuit, said 25 sending means comprising a plurality of sending rheostats connected in parallel across said source, each of said sending rheostats having an associated sender arm movable with respect thereto to select a value of control potential, 30 whereby to determine a point of balance of said control circuit, a fader resistor having a number of resistor sections corresponding to the number of said sending rheostats, said resistor sections being connected in an electrically closed 35 loop, the extremities of said resistor sections being connected to the respective sender arms, said fader resistor having an associated fader arm adapted to traverse said resistor sections in sequence to vary said control potential substantially rectilinearly with respect to said selected values, whereby to provide for gradually changing the point of balance of said control circuit within the ranges defined by said predetermined points of balance, and associated means 40 responsive to unbalance of said control circuit automatically to restore or to tend to restore balance thereof and simultaneously to operate said regulating means, whereby the degree of energization of said illumination circuit is sustained or varied as the point of balance of said control circuit is sustained or varied. 45
7. In an illumination control system, in combination, a group of electric lamps to be supplied from a source of constant potential, illumination intensity regulating means for said lamps, means for operating said regulating means, said operating means comprising sending means and receiving means connected with the latter in the form of a balancing control circuit, 50 said sending means comprising a plurality of sending rheostats connected in parallel across said source, each of said sending rheostats having an associated sender arm movable with respect thereto to select a value of control potential, whereby to predetermine a point of balance of said control circuit which determines a given intensity of illumination of said lamps, a fader resistor having a number of resistor sections corresponding to the number of said sending 55 rheostats, said fader resistor sections being connected in an electrically closed loop, the extremities of said fader resistor sections being connected to the respective sender arms, said fader resistor having an associated fader arm adapted to traverse said fader resistor sections in sequence to vary said control potential substantially rectilinearly with respect to said selected values, whereby to provide for gradually changing the point of balance of said control circuit within the ranges defined by said predetermined points of balance, and associated means responsive to unbalance of said control circuit automatically to restore or to tend to restore balance thereof and simultaneously to operate said regulating means, whereby the degree of energization of said illumination circuit is sustained or varied as the point of balance of said control circuit is sustained or varied. 60
8. In an illumination control system, in combination, a plurality of groups of electric lamps to be supplied from a source of constant potential, illumination intensity regulating means for each of said groups of lamps, operating means for each of said regulating means, said operating means comprising sending means and receiving means connected with the latter in the form of a balancing control circuit, each of said sending means comprising a plurality of sending rheostats connected in parallel across a suitable source, each of said sending rheostats having an associated sender arm movable with respect thereto to select a value of control potential, whereby to predetermine a point of balance of said control circuit which determines a given intensity of illumination of its associated group of lamps, a fader resistor having a number of resistor sections corresponding to the number of said sending rheostats, said fader resistor sections being connected in an electrically closed loop to which said sender arms are respectively connected at the points of connection of said sections, said fader resistor having an associated fader arm movable with respect thereto, means for moving said fader arms jointly with respect to said fader resistors, whereby to provide for joint and substantially rectilinear variation of the control potential for each of said control circuits between said selected values, whereby the points of balance of the respective control circuits are adapted to be changed within the ranges defined by said predetermined points of balance, and means associated with each of said control circuits and responsive to unbalance thereof automatically to restore or to tend to restore said balance, said last mentioned means being operable simultaneously to operate said regulating means, whereby the intensity of illumination of each of said groups of lamps is varied independently of the variations in illumination intensity being effected in each of the other of said groups, said intensity of illumination being varied substantially rectilinearly between the intensity values defined by said predetermined points of balance of the respective control circuits. 65
9. In an illumination control system, in combination, a group of electric lamps to be supplied from a source of constant potential, illumination intensity regulating means for said lamps, means for operating said regulating means, said operating means comprising a plurality of sending impedances connected in parallel across said source, each of said sending impedances having an adjustable sender arm associated therewith, 70

5 a receiving impedance connected in parallel with
said sending impedances and having an adjustable
receiver arm associated therewith, a fader
resistor having a number of sections correspond-
ing to the number of said sending impedances,
said fader resistor sections being connected in an
electrically closed loop to which said sender arms
are respectively connected at the points of con-
nection of said sections, said fader resistor hav-
ing 10 an adjustable fader arm associated therewith,
a polarized relay coil connected between said
fader arm and said receiver arm, said sending
impedance, receiving impedance, fader resistor
and polarized relay coil forming a Wheatstone
bridge, said sender arms being each effective to
determine a point of balance of said bridge
whereby to select given intensities of illumination,
respectively, for said lamps, said fader arm
being effective to gradually change the point of
balance of said bridge within the ranges defined
20 by said predetermined points of balance, where-
by to vary the intensity of illumination of said
lamps with respect to the values of intensity
defined by said predetermined points of balance
25 of said bridge, and means associated with said
polarized relay coil and said receiver arm and
operable by unbalance of said bridge automatic-
ally to effect adjustment of said receiver arm
to restore or to tend to restore balance of said
30 bridge, and simultaneously to operate said regu-
lating means to provide for said variation in the
illumination intensity of said lamps.

10. In illumination intensity control apparatus,
the combination with a group of electric
35 lamps to be supplied from a suitable source,
illumination intensity regulating means for said
lamps, means for operating said regulating
means, said last mentioned means comprising
sending means and receiving means connected
40 with the latter in the form of a balancing con-
trol circuit, said sending means comprising a plu-
rality of sending impedances connected in par-
allel across said source, each of said sending
impedances having an associated sender arm
45 movable with respect thereto to determine a
point of balance of said control circuit, whereby
to select given intensities of illumination, respec-
tively, for said lamps, a fader resistor having a
number of resistor sections corresponding to the
50 number of said sending impedances, said resistor
sections being connected in an electrically closed
loop to which said sender arms are connected at
the points of connection of said resistor sections,
said fader resistor having an associated fader
55 arm adapted to be moved continuously over said
resistor sections in sequence to gradually change
the point of balance of said control circuit within
the ranges defined by said predetermined
points of balance, and associated means operable
60 by unbalance of said control circuit automatic-
ally to tend to restore balance thereof and
simultaneously to operate said regulating means
to provide for variation of the intensity of illumina-
tion of said lamps between the values defined
65 by said predetermined points of balance of said
control circuit, said sender arms being so ar-
ranged, in side by side relationship, as to indi-
cate the respective intensities of illumination
preselected for said lamps by their positions in
70 their respective paths of movement and to indi-
cate the sequence in which said intensities are
enacted by said lamps, the arrangement and
relative positions of said arms being also such as

5 to indicate the relative rates at which the in-
tensity of illumination of said lamps is varied
between the preselected values, the arrangement
of said arms being such as to visually indicate
in a graphic manner, by their positions relatively
to each other, the cycle of illumination intensity
variation which said group of lamps is to afford.

11. In an illumination control system, in com-
bination, a group of electric lamps, a variable
reactor for regulating the intensity of illumina-
10 tion of said lamps, means comprising an electric
valve having a control grid and adapted to vary
the impedance of said reactor in accordance with
the voltage impressed on said grid, means com-
prising an energy storage element for impressing
15 a variable voltage on said grid, means for charg-
ing and discharging said element, a plurality of
sending potentiometer rheostats connected in
parallel and each having an associated sender
arm movable with respect thereto to preselect a
20 value of voltage to be impressed on said element,
whereby to determine a given intensity of illumina-
tion of said lamps, a fader resistor having a
number of resistance sections corresponding to
the number of said sending rheostats, said resist-
25 ance sections being connected in an electrically
closed loop to which said sender arms are respec-
tively connected at the points of connection of
said resistance sections, said fader resistor hav-
ing an associated fader arm adapted to be moved
30 continuously and unidirectionally with respect
thereto to gradually vary the voltage impressed
on said energy storage element sequentially
throughout the voltage ranges preselected by
35 said sender arms, whereby to effect gradual
variation of the intensity of illumination of said
lamps between and inclusive of said predeter-
mined intensities.

12. In an illumination control system, in com-
bination, a group of electric lamps to be supplied
40 from a source of constant potential, illumination
intensity regulating means for said lamps, oper-
ating means for said regulating means including
sending means and receiving means connected
with the latter in the form of a balancing con-
trol circuit and associated means operable by
45 unbalance of said control circuit automatically
to restore balance thereof, and simultaneously
to operate said regulating means to subject said
lamps to a degree of energization determined by
50 the point of balance of said control circuit, said
sending means comprising a plurality of po-
tentiometer resistors each having an adjustable
sender arm associated therewith for determining
a point of balance of said control circuit, a
55 fader resistor having a plurality of resistor sec-
tions connected in an electrically closed loop,
said sender arms being connected to the extremi-
ties of said fader resistor sections, respectively,
and a fader arm associated with said fader
60 resistor and adapted to traverse the sections
thereof in sequence to gradually change the point
of balance of said control circuit with respect
to said predetermined points of balance, the
resistance values of the control elements com-
65 prising said operating means being definitely
proportioned with respect to each other, whereby
upon movement of said fader arm the degree of
energization of said lamps is varied substantially
70 rectilinearly between the values corresponding
to said predetermined points of balance.
